Aaron Bull, of Carlisle, State of New York.

Letter Patent.

The schedule referred to in this Letter Patent and making part of the same containing a description in the words of the said Aaron Bull himself of his improvement in making tow-lines for towing boats on canals & for other purposes.

Be it known that I, Aaron Bull, of Carlisle, County of Franklin, State of New York, have made an improvement or discovery in making tow-lines, for towing boats on canals & for other purposes which is described as follows:

Take the tow line of hemp or any other suitable material with two or more strands, plies, or thickness & in the usual way, take brass, copper or iron wire, with or without gilding or covering, & lay it between the strands, plies, or thicknesses of the tow line, on the surface, & so as to give strength & consistency to the line, & prevent as much as possible all friction & wear.

Invention claimed. What I claim as my invention or discovery is the application of any metallic wire in making tow lines, for canal boats, & for other purposes.

For a further illustration of my invention or discovery I refer to the specimen of my tow-line & the drawing of the same, deposited in the Patent Office of the United States.

In witness whereof I have subscribed my name at the City of Washington this 5th day of January 1830.

Witness,

Aaron Bull.
